US00D915704S

(12) **United States Design Patent** (10) Patent No.: **US D915,704 S**
(45) Date of Patent: **** Apr. 6, 2021**

(54) **MOP FRAME CONNECTOR**

(71) Applicant: **CHIEF MANUFACTURING, INC.**,
Thomaston, GA (US)

(72) Inventors: **Daniel T. Fuller**, Thomaston, GA (US);
Terrance M. Renfroe, Thomaston, GA (US); **Christopher M. Bennett**,
Thomaston, GA (US)

(73) Assignee: **CHIEF MANUFACTURING, INC.**,
Thomaston, GA (US)

(**) Term: **15 Years**

(21) Appl. No.: **29/706,141**

(22) Filed: **Sep. 18, 2019**

(51) LOC (13) Cl. **07-05**

(52) U.S. Cl. **D32/50**

(57) **CLAIM**

The ornamental design for a mop frame connector, as shown and described.

DESCRIPTION

FIG. 1 is a perspective view of a first embodiment for a new design for a mop frame connector shown in an environment of use;

FIG. 2 is a rear elevation view thereof;

FIG. 3 is a left side elevation view thereof;

FIG. 4 is a top plan view thereof;

FIG. 5 is a right side elevation view thereof;

FIG. 6 is a front elevation view thereof;

FIG. 7 is a bottom plan view thereof;

FIG. 8 is a another perspective view without environment thereof;

FIG. 9 is a perspective view of a second embodiment for a new design for a mop frame connector shown in an environment of use;

FIG. 10 is a rear elevation view thereof;

FIG. 11 is a left side elevation view thereof;

FIG. 12 is a top plan view thereof;

FIG. 13 is a right side elevation view thereof;

FIG. 14 is a front elevation view thereof;

FIG. 15 is a bottom plan view thereof; and,

FIG. 16 is a perspective view another perspective view without environment thereof.

The broken lines illustrate environment of the mop frame connector and forms no part of the claimed design.

1 Claim, 4 Drawing Sheets
